UNITED STATES PATENT OFFICE.

HERMAN H. RICHMAN, OF MARINER HARBOR, NEW YORK, ASSIGNOR TO
L. STRAUS & SONS, OF NEW YORK, N. Y.

DESIGN FOR A GLASS VESSEL.

SPECIFICATION forming part of Design No. 37,225, dated November 15, 1904.

Application filed October 12, 1904. Serial No. 228,248. Term of patent 7 years.

To all whom it may concern:

Be it known that I, HERMAN H. RICHMAN, a citizen of the United States, residing at Mariner Harbor, in the county of Richmond and State of New York, have invented a new, original, and ornamental Design for Glass Vessels, the same being disclosed as applied to a bowl in the accompanying drawings, in which—
Figure 1 is a side elevation; Fig. 2, a similar view from another point, and Fig. 3 a top plan or inside view.

What I claim as new, and desire to secure by Letters Patent, is—

The ornamental design, as herein shown, for a glass vessel.

HERMAN H. RICHMAN.
